UNITED STATES PATENT OFFICE.

IRA ULFERS, OF MILWAUKEE, WISCONSIN.

ROPE LOCK.

Application filed July 11, 1928. Serial No. 291,790.

This invention relates to improvements in rope locks.

It is the primary object of the present invention to provide a rope lock designed 5 to adjustably secure a portion of a rope whereby a loop of any desired size may be formed which loop will not slip nor tighten and is well adapted for use about the neck of an animal, a post or other object.

10 A further object of the invention is to provide a rope lock adapted to be used for hitching or swing purposes whereby a rope or the like may be secured or released with great rapidity.

15 A further object of the invention is to provide a rope lock, one of which may be secured to opposite ends of a rope or cable permitting the quick formation of loops at opposite ends of the cable particularly 20 adapting the device for use in tow lines for motor vehicles.

25 A further object of the invention is to provide a rope lock of the class described which is of very simple construction, is inexpensive to manufacture, is strong and durable, and is well adapted for the purposes described.

With the above and other objects in view the invention consists of the improved rope 30 lock, and its parts and combinations as set forth in the claims and all equivalents thereof.

In the accompanying drawing in which the same reference characters indicate the same parts in all of the views:

35 Fig. 1 is a view of the end portion of a rope looped and secured by the improved rope lock;

40 Fig. 2 is a longitudinal sectional view of the rope lock on a larger scale, taken on line 2—2 of Fig. 3;

Fig. 3 is a plan view of the rope lock; and

45 Fig. 4 is a cross-sectional view thereof taken on line 4—4 of Fig. 3.

Referring now more particularly to the drawing it will appear that the numeral 6 indicates a rectangular metallic frame having rounded end portions and an elongated 50 opening 7. One end portion of the frame is formed with an extension 8 of a substantial width from which projects an eyed portion 9.

Projecting upwardly from a medial portion of one side of the frame 6 is a vertical 55 post 10 formed at its upper end portion

with an integral curved supporting arm 11 projecting at right angles to the post 10 over the opening 7 and terminating short of the outer edge of the other side of the frame. The medial portion of the supporting arm 60 11 is curved downwardly on a radius greater than that of a rope to be used with the lock and forms a seat for a portion of a rope, as shown, the curvature being indicated at 12.

In use, one end portion of a rope 13 is 65 passed through the eyed portion 9 of the lock and secured upon itself, as shown. Then, if the rope is to be hitched about an object it is wrapped thereabout and a medial portion of the rope, depending on the 70 size loop desired, is pinched and passed through the opening 7 in the frame from below. The loop portion of the rope is next passed between the side of the frame opposite the post 10 and the end portion of the supporting arm 11, as shown in dotted lines in Fig. 4, and is then brought over and seated on the curved portion of the arm. When the rope is pulled the rope portions will bind against the end portions of the frame 80 and prevent slippage and the loop will be securely maintained in its adjusted size about an object. To un-hitch the rope it is merely necessary to raise the engaged portion of the same from the arm 11 and withdraw it through the frame opening. To form a tow rope, one of the improved locks 85 may be secured to each end of the rope and then each end portion of the rope may be quickly hitched about a portion of a vehicle 90 and secured by the lock.

From the foregoing description it will be seen that the improved rope lock is of simple and novel construction, and is well adapted for the purposes set forth.

95 What I claim as my invention is:

1. A rope lock, comprising a frame having an opening therein, a post extending from a medial side portion of the frame at right angles to the plane of the same, and a rope supporting arm projecting from the outer end portion of the post at right angles thereto and spanning the frame opening.

100 2. A rope lock, comprising a frame having an opening therein, a post extending from a medial side portion of the frame at right angles to the plane of the same and integral with said frame side portion, and a rope supporting arm integral with the outer end portion of the post and projecting therefrom at 110

right angles over the frame opening and terminating short of the opposite side portion of the frame.

3. A rope lock, comprising a metallic rectangular frame having an opening therein of considerably greater length than width, a post extending from a medial side portion of the frame at right angles to the plane of the same and integral with said frame side portion, and a rope supporting arm integral with the outer end portion of the post and projecting therefrom at right angles over the frame opening and terminating short of the opposite side portion of the frame.
- 15 4. A rope lock, comprising an elongated frame member having a lock frame portion and an attaching eyed portion extending from an end thereof, the lock frame portion having an elongated opening therein greater in width than the diameter of a rope to be used therewith and of considerably greater length than width, a post extending from a medial side portion of the lock frame portion at right angles to the plane of the same, and a rope

supporting arm projecting from the outer end 25 portion of the post at right angles thereto and spanning the lock frame opening.

5. A rope lock comprising a metallic frame forming an elongated loop portion and an integral eyed portion, and an angular supporting member extending from a side of the loop portion intermediate its ends and having an outer curved bar portion spanning the loop portion.

6. In a lock of the class described, the combination with a frame member formed as an elongated loop portion with an eyed portion extending from one end thereof, of a retaining member consisting of a post projecting from a medial side portion of the loop portion and having an outer rope supporting arm at right angles to the post and spanning the loop portion and terminating short of the other side portion thereof, the medial portion of said arm being curved to form a rope seat. 40 45

In testimony whereof, I affix my signature.

IRA ULFERS.
